UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

DESIGN FOR A PADLOCK.

SPECIFICATION forming part of Design No. 32,638, dated May 8, 1900.

Application filed February 7, 1900. Serial No. 4,411. Term of patent 7 years.

To all whom it may concern:

Be it known that I, HENRY G. VOIGHT, a citizen of the United States, residing at New Britain, in the county of Hartford and State of Connecticut, have invented and produced a new and original Design for Padlocks, of which the following is a specification, reference being had to the accompanying drawing, forming part thereof.

10 The only figure of the drawing is a perspective view of a padlock, showing my design.

As shown in the drawing, the contour of the case in side view is octagonal, the several sides being of equal length and the round part of 15 the keyhole being concentric to the said equilateral sides of the octagonal contour. The

straight slot 3 of the keyhole stands centrally at a right angle to the base side 4. All of the eight sides have an oblong rectangular contour and a flat face. The shackle has a contour in harmony with the octagonal case, the whole forming a unitary design for a padlock, as shown.

Having described my invention, what I claim as new, and desire to secure by Letters 20 Patent, is—

The design for a padlock, as herein shown and described.

HENRY G. VOIGHT.
